UNITED STATES PATENT OFFICE.

WILLIAM G. KENDALL, OF NEWARK, NEW JERSEY.

COMPACT HOLDER.

Application filed December 28, 1927. Serial No. 243,094.

This invention relates to compact holders for vanity cases; and has for an object to provide an improved construction wherein a retractile holding element is provided normally acting to substantially lock the compact in place.

Another object of the invention is to provide in a vanity case, a compact holder wherein a retractile lug or bolt is associated with a holding ring so as to normally hold the compact in place but permit the release thereof at any time.

A further object of the invention is to provide a compact holder wherein a spring pressed locking member is provided, and manually actuated means for retracting the locking or holding element.

A still further object of the invention is to provide a holding device for compacts wherein a reciprocating holding bolt is presented, and a reciprocating actuating member is presented for retracting the bolt.

In the accompanying drawing—

Figure 1 is a top plan view of a vanity case with the lid shown open, and with an embodiment of the invention applied thereto.

Figure 2 is a sectional view through Figure 1, approximately on line 2—2.

Figure 3 is a sectional view through Figure 4, approximately on line 3—3, illustrating the locking bolt and certain other parts in elevation.

Figure 4 is a sectional view through Figure 3, approximately on line 4—4.

Figure 5 is a view similar to Figure 3, but showing the parts in an operated or withdrawn position.

Figure 6 is a plan view of a blank of the cam shown in Figures 3 to 5 inclusive.

Referring to the accompanying drawing by numerals, 1 indicates a casing of any usual or preferred kind. Arranged in this casing is what is commonly known as a holding ring 2 which may be formed as an annular channel iron or an L-shaped ring as preferred. Ring 2 is provided with pressed out lugs or holding members 3 and with an aperture 4 through which the bolt or holding lug 5 normally projects. This bolt is positioned to reciprocate through the aperture 4 and to be normally held in a projected position substantially as shown in Figures 1 and 3 by a spring 6. This spring 55 may be of any desired type, and as shown, is illustrated as a flat spring with a portion 7

bent back to give a proper fulcrum to the free end of the structure which carries the bolt 5. Adjacent the bolt 5 is a turned up end portion 8 which is adapted to engage the preliminary cam surface 9 and the final cam surface 10 when the cam 11 is forced into the position shown in Figure 5. When the cam 11 is moved from the position shown in Figure 3 to that shown in Figure 5, spring 6 will be swung in such a direction as to withdraw the fastening member or bolt 5, thus permitting the compact plate 12 to be ejected. This is done by inverting the vanity case and shaking the same whereupon the compact plate will drop out as the lugs 3 cannot hold the same in place when the lug or bolt 5 has been withdrawn. The bolt 5 is preferably an integral extension of the spring 6 bent to extend at right angles thereto. It is, of course, evident that it could be made of a different piece of material and secured to the spring, though the stamping of the same from the spring as shown particularly in Figure 4, is preferable, as it presents a desirable structure from a manufacturer's view point. The spring 6 normally acts to hold the bolt or pin 5 in an operative position as shown in Figure 1, while the cam 11 is adapted to move the bolt 5 to an inner position whereby compact 12 is released. The cam 11 is preferably formed from a cam blank 11' as shown in Figure 6, said blank having an extension 15 which presents an actuating pin extending through the slot 14. Blank 11' is bent along the lines indicated in Figure 6 until it assumes the shape shown in Figure 3. This cam rests on the guide 16 and the pin of extension 15 projects through the slot 14. It will be noted that the slot 14 is in the upper surface 17 of ring 2 so that the upper end of pin 15 may be readily engaged by the fingers for sliding the cam 11 from the position shown in Figure 3 to that shown in Figure 5 or in a reverse direction. The cam will remain in either position so that the bolt 5 will be normally held in an operative position when cam 11 is retracted and will be held in an inoperative position when the cam has been moved to the position shown in Figure 5.

When a compact is to be ejected, cam 11 may be pushed over to the position shown in Figure 5, and it will remain in that position until the cam has been moved back manually. If the cam 11 is moved back manually when there is no compact in the

ring 2, the compact may be readily inserted and snapped in place, as the rounded end of bolt 5 will permit this action and also the spring 6 will permit the bolt to be forced 5 out of the way as the compact is forced downwardly to the position shown in Figure 2.

What I claim is:

1. In a vanity case, a compact holding 10 ring, and retractile means for normally holding a compact in said ring.
2. A releasable holding device for releasably holding a compact in a vanity case, said holding device comprising a reciprocating 15 member acting as a locking bolt, a spring for moving said member into operative position, and a hand operated structure for moving the reciprocating member against the action of the spring.
- 20 3. In a vanity case, a holding ring provided with a plurality of pressed out lugs, said lugs being spaced apart, a reciprocating member acting as a lug co-acting with the first mentioned lugs for holding a compact 25 in said ring, and a hand operated member for moving said member out of operative position whereby said compact will be released.
- 30 4. A holding device for holding a compact in a vanity case, said holding device comprising a ring having spaced pressed out lugs and an aperture, a reciprocating member arranged in said aperture, a spring for moving said reciprocating member so that it will act as a holding lug and co-acting with the 35 other lugs for retaining a compact in said ring, and a sliding hand operated member for retracting said reciprocating member whereby said compact will be released.
- 40 5. In a device for holding a compact in a vanity case, a holding ring provided with a projection adapted to engage a compact and present a partial holding means therefor, a member positioned to co-act with said projection and act as a second projection for 45 holding a compact in said holding ring, and hand operated means for moving said member to an inoperative position.
- 50 6. A holder for holding compacts in vanity cases, comprising a holding ring adapted to receive compact holding members projecting from said ring, one of said holding members being capable of retraction, a spring for moving said last mentioned holding member in one direction, and a hand operated sliding member for moving said last

mentioned member in the opposite direction.

7. A device for holding a compact in a vanity case, said device comprising a holding ring formed with a plurality of holding members and an aperture, a sliding bolt 60 fitted in said aperture and adapted to act as an additional member, a spring for moving said bolt to a holding position, and a hand operated cam for moving said bolt to a released position.

8. A holding device for vanity cases adapted to hold a compact therein, said holding device including a holding ring carrying projections, a sliding bolt acting as an additional holding projection, a spring for 70 holding said bolt in normal holding position, and a hand operated sliding cam for actuating said bolt to move the same to a released position.

9. In a holding device for holding a compact in a vanity case, said holding device comprising a holding ring having an aperture therein and a plurality of projections, a bolt slidably mounted in said aperture, a flat spring carried by said holding ring, 80 said spring carrying said bolt and normally holding the bolt so that it will project through said aperture, and a sliding hand operated cam adapted to engage one end of said spring for retracting said bolt, said 85 cam moving substantially circumferentially of the ring.

10. A holding ring for holding a compact plate in a vanity case, and means for releasing said compact plate, said ring having a body section arranged substantially parallel to the axis of the case and a substantially radiating flange extending from the upper edge of the body section, said body section being formed with a plurality of portions 90 pressed inwardly radially for normally holding the compact plate in the ring.

11. In a vanity case, a compact plate holding ring comprising a tubular section, and a radiating section radiating outwardly 100 from the tubular section, said tubular section having means projecting inwardly radially for holding the compact plate in the ring while said radial section engages the vanity case.

Signed at New York in the county of New York and State of New York, this 22nd day of December, A. D. 1927.

WILLIAM G. KENDALL.
